UNITED STATES PATENT OFFICE.

JOHN BOWMAN AND BENJAMIN BOWMAN, OF TORONTO, ONTARIO, CANADA.

PRIMER FOR INTERNAL-COMBUSTION ENGINES.

•1,130,705.

Specification of Letters Patent.

Patented Mar. 9, 1915.

Application filed December 20, 1913. Serial No. 807,901.

To all whom it may concern:

Be it known that we, JOHN BOWMAN and BENJAMIN BOWMAN, subjects of the King of Great Britain, and residents of the city of Toronto, county of York, Province of Ontario, in the Dominion of Canada, have invented certain new and useful Improvements in Primers for Internal-Combustion Engines, as described in the following specification and illustrated in the accompanying drawings, that form part of the same.

The principal objects of the invention are, to obviate the difficulties incident to the starting of internal combustion engines in cold weather, and to provide a simple and effective priming device which may be readily attached to any form of engine and which will insure an explosive mixture reaching the cylinders.

20 A further and important object is to effect a saving of fuel in the operation of the engine.

The principal feature of the invention consists in the novel construction and arrangement of a priming device, whereby a supply of fuel spirit is introduced directly into the valve chamber and a flow of air directed through the channel through which said spirit is introduced, and whereby the air flow through said channel is controlled.

In the drawings, Figure 1 is an elevational view of the device shown applied to a four cylinder two unit engine. Fig. 2 is an enlarged elevational view of the carbureter end of the device shown in position the valve casing and intake manifold being shown in vertical section. Fig. 3 is a perspective view of the cupped carbureter end of the primer. Fig. 4 is an enlarged vertical sectional view of the fuel supply cock and air control.

Like numerals of reference indicate corresponding parts in each figure.

Referring to the drawings, 1 is the valve chamber of an internal combustion engine having the usual intake opening 2 and manifold 3 which connects the valve chambers with the ordinary carbureter.

4 are nipples inserted into the threaded holes 5 preferably arranged in the elbow of the manifold 3 slightly above the horizontal center and set at a slight incline.

6 are small tubes of copper or other suitable material extending through the nipples 4 and projecting inwardly into the valve chamber preferably with a downward in-

cline. The inner ends of the tubes 6 which extend close to the under side of the inlet valves opening into the engine cylinder are formed with cup shaped receptacles 7 preferably held in a horizontal position. The outer ends of the tubes 6 extend beyond the nipples 4 and are set at an upward incline and the tubes leading from the engine units are brought together and united in an angle connection 8.

9 is the main feed tube connected to the upper portion of the connection 8 and leading to a fuel supply member 10 which is here shown in the form of a small angle cock having a cup shaped upper portion 11. The upper edge of the cup 11 is preferably formed with a plurality of notches 12 therein which extend below the cap 13 which cap is pivotally secured to said cup and provided with a suitable spring 14 to hold it while in an open or closed position.

The valve 15 of the cock 10 is formed with a three-way passage, the main passage 16 entering at right angles to the discharge 17 and being of substantially the same diameter as the passage in the valve body.

17 is a small hole extending into the valve and communicating with the main passage 16 and so arranged that on a quarter turn 25 of the valve, the supply to the feed pipe 9 will be reduced to the diameter of the small hole.

In the use of this device, it is merely necessary to bore and tap the small hole 5 in the manifold elbows opposite the intake ports and the tubes 6 upon which the nipples 4 are arranged are then inserted through these holes and the nipples screwed into place. The passage around the tubes through the nipple may be packed in any suitable manner. The main feed tube extends to any suitable portion of the vehicle in which the engine is installed and the supply cup arranged in a suitable location.

In order to prime the engine a small quantity of priming spirit is poured into the cupped end and flowing through the valve and pipe 9 is divided equally at the connection 8 and flows through the pipes 6 to the cup shaped terminal ends 7. These cup shaped portions are preferably an integral part with the tube, the said tube being split and shaped up and presenting an elongated cup formation. The priming spirit flowing down the tube 6 lies in the cup receptacles and on the opening of the intake valves of

the engine, the suction created in the engine draws a supply of air through the tubes 6 and 9 in addition to drawing air through the manifold. The air drawn in through the hole 17 in the valve 15 flows through the tubes 6 and is required to pass through the gasoline or other priming spirit lying in the cup receptacles, being thus thoroughly carbureted and the rich carbureted air thus produced immediately adjacent to the valves 10 is drawn through the valve openings and forms an explosive mixture within the cylinder sufficient to cause the starting of the engine. Immediately following the starting of the engine the operator turns the valve 15 so as to open the larger opening and turn the small hole 17 out of alignment with the tube 9. A quantity of air is thus drawn in through the valve 10 and is directed upwardly toward the engine valves by the upturned edges of the cups 7 being thus directed through the valve openings without unduly influencing the quality of the explosive mixture drawn through the manifold 3 but a material addition is made to the volume of air drawn in through the manifold, thus increasing the volume without materially affecting the explosive quality of the gas. This effects a very considerable saving in fuel as an engine may be throttled down closer for a given speed and the auxiliary air, regulated as desired by operating the valve 15. It is found by actual tests that without changing any of the adjustments in regard to the carburetor or spark on an engine that the speed of a motor car can be increased to in the neighborhood of four or five miles an hour on an ordinary running speed by the use of this auxiliary air inlet which is a necessary adjunct to the feature of priming, as the air is taken directly through the priming spirit.

What we claim as our invention is:—

1. A primer for internal combustion engines, comprising a conduit extending into the inlet chamber adjacent to the valve and having an open receptacle secured at the inner end, said receptacle having an open area greater than the cross sectional area of the conduit and means for allowing an inflow of air through said receptacle to effect the carburation of the priming fluid.
2. A primer for internal combustion engines, comprising a conduit open to the outer atmosphere and extending into the inlet chamber and having an open cupped receptacle supported at its inner end, said

conduit being of lesser cross sectional area than the open area of the receptacle, and a receptacle at the outer end of said conduit adapted to contain a charge of priming spirit.

3. A primer for internal combustion engines, comprising a conduit open to the outer atmosphere and extending into the inlet chamber and having an open cupped receptacle supported at its inner end, said conduit being of lesser cross sectional area than the open area of the receptacle, a receptacle at the outer end of said conduit adapted to contain a charge of priming spirit, and a valve arranged in said conduit for controlling the flow of air therethrough.

4. A primer for internal combustion engines, comprising, a conduit open to the outer atmosphere and extending into the inlet chamber and having an open cupped receptacle supported at its inner end, said conduit being of lesser cross sectional area than the open area of the receptacle, and a three-way valve arranged in said conduit having a large opening to allow the free inflow of the priming spirit or air and a smaller opening adapted on the turning of the valve to restrict the flow of air.

5. A primer for internal combustion engines, comprising, a conduit opening to the atmosphere at the outer end and extending into the inlet chamber having its inner end shaped into an elongated cupped receptacle presenting an open area greater than the area of the conduit and adapted to temporarily retain a charge of priming spirit, and means arranged at the outer end of said conduit for directing the priming spirit thereinto.

6. A primer for internal combustion engines, comprising, a conduit leading to the engine valve chamber and having a cup shaped inner end, and a receptacle at the outer end of said conduit having a 3 way valve therein, said valve having a full sized opening and a reduced passage to control the flow of air therethrough.

Signed at the city of Toronto, county of York, Ontario, Canada, this 8th day of December 1913.

JOHN BOWMAN.
BENJAMIN BOWMAN.
